UNITED STATES PATENT OFFICE.

THOMAS E. CLARK, OF DETROIT, MICHIGAN.

THERMO-ELECTRIC RELAY.

1,202,362.

Specification of Letters Patent. Patented Oct. 24, 1916.

Application filed March 1, 1912. Serial No. 680,970.

To all whom it may concern:

Be it known that I, THOMAS E. CLARK, a citizen of the United States, residing at Detroit, in the county of Wayne, State of

Michigan, have invented certain new and useful Improvements in Thermo-Electric Relays; and I do declare the following to be a full, clear, and exact description of the invention, such as will enable others skilled 10 in the art to which it appertains to make and use the same, reference being had to the accompanying drawings, and to the characters of reference marked thereon, which form a part of this specification.

15 This invention relates to a thermo-electric relay or responder, adapted to be actuated by the flow of an impressed current in a receiving circuit, to close a local circuit to effect the energization of a relay placed 20 therein, or to directly or indirectly actuate electrical or mechanical instrumentalities for the performance of predetermined functions.

The invention consists in the construction, association and coöperation of parts herein- 25 after more fully set forth and pointed out particularly in the claims.

The object of the invention is to provide a simple and efficient instrument which shall respond to the flow of current in a receiving 30 circuit impressed therein from a circuit radiating high-frequency high-potential current energy. The purpose of said instrument, which is preferably in the form of a thermo-electric relay, is to utilize the current 35 energy flowing in the receiving circuit to close a local circuit or cause the actuation of electrical or mechanical devices for the control of railway signals or for other purposes.

40 The above object is obtained by the apparatus and associated circuits illustrated in the accompanying drawings in which—

Figure 1 is a plan view of the thermo- 45 electric relay showing in detail the construction thereof and also illustrating a local circuit connected therewith and the receiving circuit in which said relay is included. Fig. 2 is a transverse section through said thermo-electric relay as on line 2—2 of Fig. 1. Fig.

50 3 is a diagrammatical view showing my thermo-electric relay in a receiving circuit adapted to have impressed therein a current flow from a radiating circuit, which latter circuit is connected adjustably with a circuit 55 in which high-frequency high-potential os-

cillating currents are generated. Said view also illustrates a local circuit connected with the thermo-electric relay to be opened and closed by the operation thereof. Fig. 4 is a similar view with the generating and radiating circuits omitted, showing the thermo-electric relay as having responded to the flow of current in the receiving circuit and closed said local circuit. Fig. 5 is a perspective view of the rotatable commutator 60 of the thermo-electric relay, through the operation of which the local circuit is opened and closed. Fig. 6 is a sectional view of said commutator transversely of its shaft.

Referring to the drawings and the char- 70 acters of reference thereon, 1 designates a suitable base of insulating material. Mounted upon said base is a suitable case 2 also of insulating material, in which the parts comprising the thermo-electric relay are located. 75 Rigidly secured to the back of the case 2 is a metal bracket 3, having laterally extending and slightly flexible portions 4, provided with laterally extending curved arms 5. Connecting the curved arms of the exten- 80 sions 4 of the bracket is a strong curved spring 6. Engaging the upper arc of said spring is adjusting screw 7, which is threaded in a suitable support 8. Mounted in the ends of the lateral extensions 4 of said 85 bracket at the point of juncture of the curved arms 5 therewith, are the posts 9, which are insulated from the bracket by the insulating blocks 10. Extending be- 90 tween and electrically connecting the posts 9 is a fine wire filament 11 of high resistance and low temperature coefficient and preferably of non-oxidizable metal.

The receiving circuit in which this thermo-electric relay is located comprises a harp 12 95 consisting of a plurality of wires, the line 13, leading from said harp to a binding post 14 on said thermo-electric relay. From said binding post the receiving circuit continues on the conductor 15 to one of the conducting 100 posts 9, thence on the fine wire filament 11 to the other post 9, from which leads a conductor 16 to a binding post 17. From said binding post 17 the remaining portion of the receiving circuit comprises the line 18, 105 the variable inductance 19, with which said line is adjustably connected, and the ground 20. It will therefore be understood that the fine wire filament 11 is included in and forms a part of said receiving circuit. The 110

functions of the harp 12 are the same as those of the receiving antennæ of wireless-telegraph mechanisms.

Connected to the central portion of the 5 wire filament 11 is a fine cord 21, preferably of silk, whose lower end is wound about a shaft 22, journaled at its ends in a metallic bracket 23, supported in the case of the relay. Fastened to the shaft 22 at one end 10 and secured at the other end to a fixed pin 24, on the bracket 23, is a coiled spring 25. The tension of said spring is normally exerted to rotate the shaft 22, and the tendency of said shaft to turn is resisted by the 15 silk cord 21, which, through the tension of the spring, exerts a continual downward stress upon the wire filament 11.

A proper tension is maintained on the wire 11 through the medium of the screw 7. 20 By manipulating said screw a downward pressure may be exerted upon the spring 6, which, being connected with the arms 10 of the laterally extending portions 4 of the bracket 3, will cause a slight spreading of 25 said arms and the placing of a longitudinal stress upon the filament 11. It will therefore be seen that by a manipulation of said screw the tension on the filament 11 may be regulated in accordance with the requirements under working conditions.

The thermo-electric relay as herein illustrated is employed for closing a local electric circuit, comprising a source of energy 26, the line 27 leading therefrom to binding 35 post 28, the lines 29 leading from said binding post to the pillars 30, upon which the contact arms 31 are mounted, through said arms and the contact plates 32 set in the disk 33 of insulating material carried on the 40 shaft 22, and electrically connected with said shaft as shown in Fig. 5; the other side of said local circuit being completed on line 34 which leads from the frame or bracket in which said shaft is mounted to binding 45 post 35, and thence on line 36 through relay 37 to source of energy 26.

The local circuit just described is normally open at the insulating disk 33, the terminals of the contact arms 31 resting 50 upon the periphery of said insulating disk, out of contact with the plates 32, as shown in Fig. 3, except when the thermo-electric relay is actuated in response to the passage of a current over the receiving circuit.

55 When current is impressed upon the receiving circuit from a circuit 38 adapted to radiate high-frequency high-potential currents, the passage of such current over the filament 11 of the thermo-electric relay 60 will heat said filament and cause it to expand and sag, thereby allowing the spring 25 to rotate the shaft 22 sufficiently to cause the contact plates 32 in the disk 33, to make electrical contact with the terminals of the 65 contact arms 31, effecting a closing of the

local circuit through the relay 37, and energizing said relay to actuate the armature 39 thereof to engage the contact point 40, and close a second circuit 41 having therein a source of energy 42 adapted to energize 70 an element 43 for the performance of any desired function, a situation illustrated in Fig. 4. Upon a cessation of current in the receiving circuit, the fine wire filament 11 will cool and contract, thereby drawing 75 upwardly upon the cord 21, and turning the shaft 22 such distance as to carry the contact plates 32 thereon out of engagement with the terminals of the contact arms 31, and open said local circuit. It will be 80 noted that the contact arms 31 are in shunt with one another, an arrangement which provides for the closing of the local circuit by contact of either one of said arms with a contact plate on the rotatable disk 33. 85

This thermo-electric relay is designed for use in a receiving circuit in connection with a generator of high-frequency high-potential oscillating currents and a radiating circuit associated therewith adapted to impress 90 upon said receiving circuit a current of high-frequency high-potential energy. In Fig. 3 I have diagrammatically illustrated one form of such a generator and of such a radiating circuit, which I will now describe as 95 follows: An alternating current generator 44 is connected through circuit lines 45 and 46, including a reactance regulator 47 and a suitable switch 48, with the primary of a transformer 49. Connected across the 100 terminals of the high-potential secondary of the transformer 49 is a spark gap 50. A high-potential oscillating circuit is formed to include said spark gap by means of the lines 51 and 52, in each of which is 105 included a condenser 53. To complete said high-potential oscillating circuit, there is included therein one or more turns of an inductance or linking coil 54, the line 51 of said high-potential oscillating circuit being 110 adjustably connected to said linking coil in the usual manner in order to vary the inductance in said circuit. The radiating circuit 38 is adjustably connected with the inductance 54 through the line 55. The 115 closing of the spark gap in the high-frequency oscillating circuit is effected through the medium of a disk 56 adapted to rotate at high velocity and having thereon laterally projecting conducting studs 57, which, as the disk revolves, pass between the electrodes 58 of the spark gap. The spark gap electrodes are so adjusted as to form between them an air gap which is normally 120 too great for the oscillating current to spark across. As the disk 56 revolves, the projecting studs thereon passing between the electrodes shorten the air gap between them, thereby enabling the current to spark across 125 said gap, and causing high-frequency high- 130

potential oscillating-current discharges to take place in the oscillating circuit. If the 5 sparking disk be timed in its rotation with respect to the capacity and inductance of the radiating circuit, said circuit will radiate the electrical energy supplied to it from the generating circuit, and will continue, while said condition obtains, to radiate 10 electrical energy of a frequency and potential depending upon the adjustment or tuning of the high-frequency oscillating circuit. When high-frequency high-potential current is being generated as described, and radiated from the radiating circuit 38, and 15 the harp or collector 12 of the receiving circuit is disposed in proximity to said radiating circuit, a strong flow of high-potential current will be impressed upon said receiving circuit of a value varying in 20 accordance with the tuning thereof, and will actuate the responder or thermo-electric relay placed in said receiving circuit to close a local circuit as before described, or to perform such other functions as may properly 25 come within the scope of an instrument of this character.

By heavily insulating the parts included in the receiving circuit or forming a path for the receiving circuit current, a high- 30 frequency high-potential current may be readily utilized to actuate the responder or thermo-electric relay as described.

This responder or thermo-electric relay is especially desirable for use in connection 35 with signaling and train controlling devices, employed in block signal systems of train control, where said devices are mounted on a locomotive or other movable vehicle, and where the thermo-electric relay or responder which renders said devices operative or inoperative must also be carried upon 40 said locomotive or other vehicle, and subject to the jar and vibration incident to the operation of a railway locomotive. This 45 thermo-electric relay is not affected by the jar or vibration of a locomotive or any other movable vehicle upon which it may be mounted, and will respond to the flow of a current through the receiving circuit to close 50 a local circuit or perform any other function as effectively when the locomotive is moving at a high rate of speed, as it would were the locomotive standing still. The construction of the instrument is such that upon 55 the breaking of the cord 21 or the breaking of the filament 11, the spring 25 will revolve the shaft 22, so as to carry the contact plates 32 in the insulating disk 33 to a point out of contact with the arms 31 in the local 60 circuit, thereby obviating the accidental

closing of the local circuit through injury or accident to the responder or thermo-electric relay.

Having thus fully set forth my invention, what I claim as new and desire to secure by Letters Patent is:—

1. In a thermo-electric relay, a filament of high resistance forming a part of a receiving circuit, a local circuit, a rotary disk of insulating material carrying a contact plate forming one terminal of said local circuit, a spring contact forming the other terminal of said local circuit, adapted to normally engage the periphery of said rotary disk, a strand connected to said disk at one end and at the other end engaging said filament, and means for rotating said disk to place a tension upon said strand. 70

2. In a thermo-electric relay comprising two insulated terminal posts, a filament forming a path for an electric current extending between and connecting said posts, means for varying the tension on said filament, a rotatable disk of insulating material, a contact plate thereon forming a terminal of a local circuit, a spring contact arm forming the other terminal of said local circuit, normally engaging the periphery of said disk, and means operatively associated with said parts and actuatable by a flow of current over said filament to cause said disk to rotate and carry the contact plate thereon into engagement with said contact arm and close said local circuit, said means being operative to turn said disk in the opposite direction and open said local circuit, upon a cessation of the current flow over said filament. 85

3. In a thermo-electric relay, the combination of a pair of supports, a filament tensioned between them and adapted to receive current energy, a local circuit containing a spring contact, a rotary disk of insulating material having a contact plate, means for turning the rotary disk to such position that the contact plate thereon engages the spring contact, a flexible connector between the middle portion of the filament and extending therefrom to said disk to hold the contact plate out of engagement with the spring contact until a proper current over the filament causes the same to expand and thereby permits the disk to turn to permit engagement of the plate and spring contact. 100

In testimony whereof, I sign this specification in the presence of two witnesses.

THOMAS E. CLARK.
